UNITED STATES PATENT OFFICE.

WILLIAM R. HADDOCK, OF SOUTH BEND, WASHINGTON.

TRANSFER-SHEET.

1,261,516.

Specification of Letters Patent.

Patented Apr. 2, 1918.

Application filed April 21, 1917. Serial No. 163,633.

To all whom it may concern:

Be it known that I, WILLIAM R. HADDOCK, a citizen of the United States, residing at South Bend, in the county of Pacific and State of Washington, have invented new and useful Improvements in Transfer-Sheets, of which the following is a specification.

This invention relates to transfer sheets such as are commonly used on typewriting machines for obtaining and producing carbon copies.

The object of the invention is to produce a transfer sheet having a tear off line designated thereon parallel to one of the edges of the sheet and located at a distance from said edge approximately equal to one-half of the distance between the lines of typewriting.

A further object of the invention is to secure a different registration between the transfer sheet and the ribbon sheet and follow sheet. This enables unused lines or portions of the carbon sheet to be brought into position to transfer the impressions to the follow sheet, practically doubling the life of the carbon sheet.

A further object of the invention is to provide a transfer sheet having lines of perforations extending transversely thereof and so arranged as to accomplish the result above set forth when used either in connection with legal-cap paper or the letter-head size.

With the above and other objects in view, the invention consists in the novel construction, combination and arrangement of parts herein fully described, illustrated and claimed.

In the accompanying drawings:—

Figure 1 is a plan view of the transfer sheet used in connection with legal-cap paper,

Fig. 2 is a similar view showing a numbered ribbon sheet combined with the transfer sheet, the ribbon sheet being partially elevated,

Fig. 3 is a view similar to Fig. 2 showing the relation between the ribbon sheet and the carbon sheet and follow sheet after a strip has been torn from the transfer sheet along one of its lines of perforations,

Fig. 4 is a plan view of a transfer sheet designed for use in connection with ribbon and follow sheets of legal-cap or letter-head size.

Referring to the drawings A designates a ribbon sheet of paper, B the transfer sheet,

and C a follow sheet, the transfer sheet being as usual interposed between the ribbon sheet and the follow sheet with its prepared surface toward the follow sheet and its unprepared surface toward the ribbon sheet.

The transfer sheet is particularly designed with reference to its use in combination with a ribbon sheet having a side marginal row of numerals or other designating characters indicated at D so that the lines of typewriting may register with said numerals or characters, but it will of course be understood that the use of the transfer sheet is not limited to paper provided with line-designating characters.

The transfer sheet B is provided with a line of perforations *a* extending parallel to one of the shorter edges of the sheet and it may also be provided with another row of perforations *b* extending parallel to the other shorter edge of the paper. The distance between each row of perforations *a* or *b* and the adjacent edge of the sheet is substantially one-half the distance between the lines of typewriting so that when the marginal strip of the transfer sheet is removed by tearing or otherwise, and the transfer sheet is lined up with the corresponding edges of the ribbon and follow sheets, the worn or used portions of the transfer sheet will be moved out of line with the ordinary lines of typewriting and the unused portions of the transfer sheet will be moved into the lines of writing thereby giving as clear an impression as would be given by a new transfer sheet. This practically doubles the life of a sheet of transfer paper.

The transfer sheet B may, if desired, be also adapted for use in combination with ribbon and follow sheets of a smaller size than legal-cap as for example, sheets of letter-head size. In such case the transfer sheet will be provided with another row of perforations *c* so that the smaller portion of the sheet at one side of the line of perforations *c* may be torn off or otherwise removed leaving the transfer sheet of the same size as the ribbon sheet and follow sheets. In addition to the line of perforations *c* another line of perforations *d* is provided, the perforations *d* extending along a line parallel to the row of perforations *c* and being located a distance from the line *c* equal to approximately one-half the distance between the lines of normal typewriting. The use of the sheet of reduced size is the same as that

previously described. The smaller sheet ending at the line *c* is lined up with the corresponding marginal edges of the ribbon sheet and follow sheet and after the transfer sheet has become too far worn for further use, the strip between the lines of perforations *c* and *d* is removed so that by lining up the transfer sheet of reduced size with the ribbon sheet and follow sheet, the 10 unused portions of the transfer sheet will register with the lines of typewriting, with the same result as hereinabove described.

What is claimed is:—

1. As an article of manufacture, a transfer sheet having a tear-off line of perforations extending parallel to one of the edges thereof and located at a distance from said edge approximately equal to one-half the 15 distance between the normal lines of impressions.

2. A transfer sheet for use in typewriting

machines, having a line designated thereon parallel to one of the edges thereof and located at a distance from said edge approximately equal to one-half of the distance between the lines of typewriting, for the purpose specified. 25

3. A transfer sheet for use in connection with typewriting machines, having a plurality of rows of perforations all extending parallel to one of the edges of the sheet and forming a plurality of tear-off portions, enabling the sheet to be reduced in size from one standard size of paper to another and to be additionally reduced in size to effect a 30 different registration between the transfer sheet and the ribbon sheet and follow sheet, substantially as and for the purpose described. 35

In testimony whereof I affix my signature. 40

WILLIAM R. HADDOCK.
